UNITED STATES PATENT OFFICE.

WILLIAM E. CRUME, OF DAYTON, OHIO, ASSIGNOR TO THE CRUME & SEFTON MANUFACTURING COMPANY, OF SAME PLACE.

PAPER RECEPTACLE.

SPECIFICATION forming part of Letters Patent No. 394,158, dated December 11, 1888.

Application filed August 15, 1888. Serial No. 282,819. (No model.)

To all whom it may concern:

Be it known that I, WILLIAM E. CRUME, a citizen of the United States, residing at Dayton, in the county of Montgomery and State 5 of Ohio, have invented a certain new and useful Improvement in Paper Receptacles, of which the following is a full, clear, and exact description.

My invention relates to an improvement in 10 paper receptacles designed to contain merchandise in either liquid or solid form, in which a sheet of paper or similar flexible material is folded by creasing it into a rectangular bag or vessel with flat bottom and sides, 15 and the sides extended up so as to be bent or folded toward one another at an obtuse angle to the sides, their edges being fastened together to close the receptacle as in the manner familiar in the construction of traveling-bags and the like. The upper portions of the 20 ends are creased inward or folded upon themselves to completely close the vessel.

The novel features of my invention will be 25 more fully hereinafter set forth.

In the accompanying drawings, illustrating 30 the invention, like letters represent identical parts in the various figures.

Figure 1 represents a single sheet of paper which has been formed into a receptacle and 35 is flattened out, showing the creases used or produced in folding by dotted lines. Fig. 2 is a view in perspective of my improved receptacle closed and fastened and provided with a carrying-bale. Fig. 3 is a view in perspective of the receptacle open. Fig. 4 is a 40 view in perspective showing a modified form of the closed receptacle in which the upper parts of the ends are not folded in, but upon themselves to produce an end wall, all in the same plane and unbroken. Fig. 5 is a similar view to Fig. 4, showing the receptacle open. Fig. 6 is a sheet of paper flattened out, cut, and creased to produce the form of receptacle shown in Figs. 4 and 5, with the unbroken 45 ends.

In producing the vessel the sheet of paper is cut in the form shown and scored as indicated by the dotted lines to cause it to crease or fold as desired. The four corners *xx* being then drawn upward and together and the edges forced inward, the sheet is folded at the

55 scores, forming the receptacle A, having a flat base or bottom and straight or flat sides and ends. The flaps or folds formed by folding the sheet upon itself are all brought within the vessel and folded against or parallel with the sides, where they are fastened by the wire staples B or in any well-known manner. These 60 folds being thus arranged and fastened give the vessel greater stiffness and strength, and the folds or surplus paper being folded inward leave the outside surface plane. This is important as producing a better appearance and providing a plane surface upon which to print or stamp upon the receptacle 65 any matter which may be desired. The upper portions of the sides are creased at C and pressed or bent toward one another, one of them being provided with an extension-flap, 70 D, which is folded over the other, as seen in Figs. 2 and 4, thus completely closing the top of the vessel. The upper portion of the ends may be folded in two ways, as shown in Figs. 1 and 6. The creases G G may be made to come together at the edge of the paper, as in 75 Fig. 1. When the end extensions are folded in at an angle to the ends proper and beneath the extensions of the sides, there is an exterior triangular recess at each end of the box, as is shown in Figs. 2 and 3; but when the creases 80 G G are carried to the edge of the end extension at a distance apart, as in Fig. 6, and the creases H H are provided, then when the end extensions are folded inward the fold-lines of the central portions meet the fold-lines at the 85 ends of the side extensions in the plane of the end proper, as shown in Figs. 4 and 5, leaving the ends unbroken and all in the same plane, without the exterior triangular recess. 90

In order to fasten the receptacle shut I provide, attached to the flap, a flexible strip or strips, K K, preferably of thin sheet metal, though any material—such as tapes or strings—may be used. These strips K K may 95 be passed through the side at the crease where it is joined to the flap D, or through the flap D itself, and bent over and tied or fastened. When the flap D is folded over the edge of the opposite side, as in Figs. 2 and 4, these 100 strips K K are passed under the staples B B and bent or secured by tying in any conven-

int way, thus effectually closing and securing the vessel, the staples B B in this construction of receptacle serving a double purpose—to fasten the folds to the sides and hold the 5 receptacle in shape and to lock the lid. The bail or handle may be provided in any convenient way or of any desired material. I prefer to use a wire bail, M, the ends of which are passed inwardly through the side carrying the flap D at the crease or hinge where the flap D joins the side, as that becomes the apex of the receptacle when closed, and then carried out to the ends of the receptacle and bent up and around the lid or extended side, 10 as shown at N. It thus provides a secure fastening and gives additional strength and stiffness in binding together the sides and the inner folds.

Having fully described my invention, what 20 I claim, and desire to secure by Letters Patent of the United States, is—

1. A paper receptacle having a cover integral with it and comprising defined extensions of the sides of the receptacle, which incline 25 at an angle to the sides when brought together to close the receptacle, one of these sides being provided with an extension or flap to fold over the other to completely close the receptacle, and provided with means for securely fastening the same, substantially as and for the purpose described.

2. A paper receptacle having a cover integral with it and comprising defined extensions of the unsevered sides of the receptacle, which 35 incline at an angle to the sides of the receptacle when brought together to close the receptacle, one of the sides being provided with an

extension or flap to fold over the edge of the other side, in combination with the strips K K and staples B B, substantially as and for 40 the purpose described.

3. A receptacle formed of a single sheet of paper, the top consisting of extensions of the sides folded together, the sides re-enforced by the inwardly-folded flaps, the clamping device B, fastening the folds and the sides together, and the lock or fastening of the cover engaging the clamping device, substantially as and for the purpose specified.

4. A paper receptacle having a cover integral with it, and consisting of the extended sides of the receptacle folded together over the inwardly-folded ends, one of these sides provided with an extension or flap to fold over the other, and a handle, M, attached at 50 the hinge or crease, which becomes the apex of the vessel when closed, substantially as and for the purpose described.

5. In a paper receptacle having a cover integral with it and comprising defined extensions of the sides of the receptacle, which incline at an angle to the sides of the receptacle when brought together to close the receptacle, the end extensions having fold-lines and folded inward, so that the fold-lines of 60 the central portions meet the fold-lines at the ends of the side extensions in the plane of the end proper, substantially as and for the purpose described.

WILLIAM E. CRUME.
